UNITED STATES PATENT OFFICE.

JOSEPH SMITH BURT, THOMAS WOTHERSPOON BURT, GEORGE PETER BURT, AND JOHN WOTHERSPOON BURT, OF GLASGOW, SCOTLAND.

WRINGING MACHINE.

Application filed April 9, 1923. Serial No. 630,835.

To all whom it may concern:

Be it known that we, JOSEPH SMITH BURT, THOMAS WOTHERSPOON BURT, GEORGE PETER BURT, and JOHN WOTHERSPOON BURT, subjects of the King of the United Kingdom of Great Britain and Ireland, and residing at Mile-End, Glasgow, Scotland, have invented a certain new and useful Improvement in Wringing Machines, of which the following 10 is a specification.

This invention relates to wringing machines in which the brackets for supporting the machine frame are adapted to swivel relatively to the machine frame.

15 The invention consists in a wringing machine in which the brackets are each formed with a single clamp attachable to the machine frame for swivelling movement with the clamps in either of two positions at right angles to one another.

According to a preferred construction the wringing machine is provided with brackets each having a single clamp and each provided with two sockets the axes of which are 25 disposed at right angles to one another, the sockets being engageable with a stud on the machine frame.

Fitted to each bracket is a locking pin which is common to both sockets and is 30 adapted for engagement with a groove on the stud which merges into a flat on the cylindrical surface of the stud, the arrangement being such that the socket may be slid on to the stud with the locking pin rubbing 35 the flat and then rotated so as to bring the pin into engagement with the groove.

The invention is illustrated in the accompanying drawing in which Fig. 1 is an elevation showing a bracket with the clamps in 40 position for engagement with a vertical support, Fig. 2 is an elevation showing the clamp in position for engagement with a horizontal support and Fig. 3 is a section showing the locking pin about to enter the 45 groove.

The bracket shown has a single clamp 1

and is provided with two sockets 3, 4 the axes of which are disposed at right angles to one another, the sockets 3, 4 being engageable with a stud 5 depending from the 50 machine frame 9. Fitted to the bracket is a locking pin 6 which is common to both sockets 3, 4 and is adapted for engagement with an annular groove 7 on the stud 5, which groove merges into a flat 8 on the cylindrical surface of the stud, the arrangement being such that a socket may be slid 55 on to the stud 5 with the locking pin 6 rubbing on the flat 8 and the bracket then rotated so as to bring the pin into engagement 60 with the groove 7.

What we claim is:—

1. In a wringing machine the combination with a frame having a stud, of a clamp bracket having two sockets in either of 65 which said stud has a sliding fit so that said stud may be removably entered into said bracket in either a vertical or horizontal position, and a pin for locking said bracket to said stud when the clamp is in working 70 position.

2. In a wringing machine, the combination with a frame having a stud formed with a groove and a flat, of a bracket provided with two sockets having their axes at right 75 angles to one another, said sockets engageable with said stud, and a locking pin engageable with the groove, whereby the bracket may be slid on to the stud with the locking pin rubbing on the flat and then rotated 80 to bring the locking pin into engagement with the groove.

In testimony whereof we have signed our names to this specification in the presence of two subscribing witnesses.

JOSEPH SMITH BURT.
THOMAS WOTHERSPOON BURT.
GEORGE PETER BURT.
JOHN WOTHERSPOON BURT.
